METHOD OF PRODUCING CONTINUOUS STRINGER WORKPIECES WITH CONTINUOUS COVERING MEMBERS THEREON

Louis H. Morin, Bronx, N.Y., assignor to Coats & Clark Inc., New York, N.Y., a corporation of Delaware

Filed Nov. 4, 1958, Ser. No. 771,796

1 Claim. (Cl. 112—265)

This invention relates to the production of separable fastener stringers employing stringer tapes, with scoops spaced longitudinally of a beaded edge of the stringer and, wherein, each stringer has protruding mounting tape ends extending beyond end scoops of the stringer. More particularly, the invention deals with the method of producing separable fasteners of the character described, wherein the stringers are first formed in what I term a continuous stringer workpiece, including continuous covering members in the form of tapes, ribbons or other strands, disposed upon opposed surfaces of and stitched to the workpiece in a continuous line of stitching, which extends over the mounting end portions of scoops and continuously and uninterruptedly through substantially the central portion of said covering members and onto said members in the spacing of the mounting tape between adjacent groups of scoops on the workpiece.

Still more particularly, the invention deals in a method as defined, wherein the covering members are maintained substantially in a common alinement along the beaded edge of the stringer tapes and the mounting end portions of the scoops in such manner as to expose inner surfaces of the mounting end portions of the scoops to be engaged by the slider employed with devices of this type and kind in coupling and uncoupling a pair of stringers.

The novel features of the invention will be best understood from the following description, when taken together with the accompanying drawing, in which certain embodiments of the invention are disclosed and, in which, the separate parts are designated by suitable reference characters in each of the views and in which:

Fig. 1 is a diagrammatic plan view of a portion of a stringer workpiece primarily illustrating the spacing of the stringer tape between spaced groups of scoops defining stringer lengths and illustrating the stitching of one of the covering tapes to a surface of the workpiece.

Fig. 2 is an enlarged diagrammatic perspective view illustrating somewhat more in detail the arrangement of a few scoops on the beaded edge of a stringer tape and indicating the two covering members stitched to the tape and to part of the spaced portion of the tape between groups of scoops, diagrammatically illustrated in Fig. 1.

Fig. 3 is a partial section on the line 3—3 of Fig. 2; and

Fig. 4 is a partial section on the line 4—4 of Fig. 2, with part of the construction broken away.

In the production of separable fastener stringers in accordance with my improved method, an elongated substantially endless stringer tape is fed into and through a casting machine for forming groups of scoops along the beaded edge of the stringer tape, the groups of scoops defining a stringer length. These stringer lengths vary, depending upon the lengths that are required and this substantially endless formation of the spaced groups of scoops on the stringer tape, I will define, for purposes of description, as a workpiece.

2

The workpiece is then fed through a stitching or sewing machine, where two covering members are arranged upon upper and lower surfaces of the workpiece over the mounting end portion of the scoops and stitched in position by a line of stitching disposed substantially centrally of said members and these members are arranged to extend along and be stitched to the stringer tape in the continuous line of stitching and so timed as to pick up the next successive groups of scoops, thus producing the continuous resulting end product, comprising the tape with the groups of scoops thereon and the covering members stitched thereto; whereupon, the workpiece is severed substantially centrally between the spaced groups of scoops in defining the stringer lengths, each having, at the ends thereof, plain portions utilized in attachment of the stringers to the products, in connection with which the fasteners are employed.

In Fig. 1 of the drawing, 10 represents an elongated stringer workpiece, part of which is shown on an enlarged scale and in perspective in Fig. 2 of the drawing, the tape having an enlarged or beaded edge 11, as clearly noted in Figs. 3 and 4 of the drawing. At 12 and 12' I have shown in Fig. 1 of the drawing a few scoops at ends of spaced groups of scoops on the workpiece; stringer 10 and part of the scoops 12 are also diagrammatically illustrated in Fig. 2 of the drawing.

Between the groups 12, 12', the workpiece includes a spacing portion 13, on which the attachment of scoops has been omitted and, in carrying out my method, this spacing portion is later severed substantially centrally, as indicated at 14, to provide, on each end of the groups of scoops, fastener securing portions 15, 15'.

In Fig. 1 of the drawing, I have indicated at 16 an upper covering member, which is also illustrated, in part, in Fig. 2 of the drawing and, in Fig. 2, as well as in Figs. 3 and 4, I have shown the opposed or lower covering member at 16'. These members can be formed of ribbons, tapes, cords or other elongated members of any suitable material and of such width as to cover the mounting end portions 17 of the scoops 12, 12', as clearly noted in Fig. 2 of the drawing, but positioned so that the inner edges 18, 18' of the covering members are disposed in alinement with inner surfaces of the mounting end portions 17, as clearly noted in Fig. 4 of the drawing. By this method of procedure, the inner surfaces of the mounting end portions 17 of the scoops are exposed for engagement with the slider, which is movable along the stringers in coupling and uncoupling stringers, as is well known in the separable fastener art.

Considering Fig. 4 of the drawing, it will appear that the mounting end portions 17 of the scoops have vertically and upwardly and downwardly flaring apertures 19. In illustrating one adaptation and use of my method, the scoops 12, 12' are preferably made of plastics and plastics such as Delrin can be used.

At 20 in the several views, I have shown the stitchings which extend centrally along the coverings 16, 16' and pass through the apertures 19 of the scoops and through part of the beaded edge 11 of the stringer tape, as clearly indicated in Fig. 3 of the drawing, the covering members being maintained in an alinement along the stringers or the workpiece, as noted in Fig. 1 of the drawing and, by maintaining this longitudinal alinement, the resulting end product stringers will be practical for their intended use.

The spacing of the stitchings 20 on the covering members and stringers and with respect to the scoops is such as to register with the apertures 19 of all of the adjacent scoops and to extend along the spacing section 13 and then pick up the next end scoops of the adjacent group of scoops, in the manner diagrammatically illustrated in

Fig. 1 of the drawing, this result being accomplished without interference with or changing the continuous cycle of operation of attachment of the covering members to the stringers. Considering Fig. 1 of the drawing, it will be apparent that the securing portion, or end 15, may be said to define the upper end of a resulting stringer; whereas, the end 15' would define the lower end of the next adjacent stringer of the workpiece, as diagrammatically illustrated in Fig. 1. In other words, each resulting stringer formed by severing the workpiece on the dotted line 14 will provide an end 15 and an end 15' thereon and these ends will include the stitched-on covering members 16, 16'.

Comparing Fig. 3 with Fig. 4 of the drawing, it will appear that the members 16, 16' maintain substantially their same relative position upon the stringer tape 10, thereby maintaining the common alinement of these members along the stringers, including the ends 15, 15' thereof.

With my improved method, the single line of stitching will maintain the covering members in position and, at the same time, will reinforce, to a degree, the attachment of the scoops to the stringer by virtue of passing of the stitchings through the apertures 19 in each of the scoops.

By virtue of my improved method, the resulting end product can be produced very efficiently and at a high rate of speed, thus minimizing the cost of production. The particular characteristics of the covering members will vary on different types and kinds of fasteners, depending upon the use to which they are to be applied and this is also true of the material employed in the stringer tape. In addition to structural characteristics, both the tape and the covering members can be produced in materials of different colors to suit or match the products in conjunction with which the fasteners are employed.

Having fully described my invention, what I claim as new and desire to secure by Letters Patent is:

The method of producing separable fastener stringers employing covering members on apertured mounting end portions of scoops of the stringers, with inner end surfaces on said mounting end portions adapted to be en-

gaged by a slider movable along the stringers for stringer coupling and uncoupling action, which method comprises forming groups of scoops on the beaded edge of a stringer tape with wide spacings between adjacent groups of scoops, placing elongated covering members in position in substantial alinement to the outer beaded edge portion of the stringer tape and to the scoops with the inner edges of said covering members along said groups of scoops free from substantial projection beyond the inner surfaces of the mounting end portions of the scoops to expose said inner surfaces for engagement with the slider, stitching said covering members in said position with a line of stitching extending along said covering members and with such registry as to cause the stitchings to pass through the apertures respectively in the mounting end portions of the scoops, continuing the stitching of the covering members along the beaded edge portion of the stringer tape and along the spacings between groups of scoops on the stringer tape, with stitching of the same type and spacing as that passing through the apertures of the scoops, and with no interruption in the continuity of the stitching in its transition from the scoops to the spacings to the scoops, whereby stitching along the groups of scoops and along the spacings can be carried out by a continuous cycle of operation and whereby a stringer workpiece is produced, and then severing the spaced portions of the workpiece between adjacent ends of groups of scoops and at regions spaced from adjacent groups to form predetermined stringer lengths of said workpiece.
